ELECTRIC GRIDDLE

Original Filed Sept. 12, 1925 2 Sheets-Sheet 2

INVENTOR.
Karl Ehrgott,
BY Edward A. Lawrence
his ATTORNEY.

UNITED STATES PATENT OFFICE.

KARL EHRGOTT, OF ERIE, PENNSYLVANIA, ASSIGNOR TO BERNARD GLOEKLER COMPANY, OF PITTSBURGH, PENNSYLVANIA, A CORPORATION OF PENNSYLVANIA.

ELECTRIC GRIDDLE.

Application filed September 12, 1925, Serial No. 56,046. Renewed September 27, 1927.

More particularly my invention comprises improvements in the griddle top and the mounting of the heating elements therein, and also to the structure of the base and the 5 mounting of the insulating element therein.

In the accompanying drawings, wherein I have illustrated the best embodiment of the principles of my invention now known to me, Fig. 1 is a front elevation of the electric griddle, broken away in partial section along the line I—I in Fig. 2 to show parts; Fig. 2 is a bottom plan view of the griddle top on reduced scale; Fig. 3 is an end view of the electric griddle looking from the left in Fig. 10 1, the same being broken away in partial section along the line III—III in Fig. 2; Fig. 4 is a detail in section showing the means for securing the ends of the heating elements; Fig. 5 is an enlarged detail 15 section along the line V—V in Fig. 2; Fig. 6 is a broken plan view of the insulating element and its pan, and Fig. 7 is a perspective of the locking member which connects together the bottom parts.

20 Referring in detail to the drawings, A represents the griddle top which is supported by the inclosed base B, the base being supported at proper elevation by the feet C. D represents the heating elements mounted in 25 the top. E represents the insulating member, usually a mat of suitable material, such as asbestos felt, and which is contained in a pan F mounted in the base B.

The construction of the top, as shown, is as 30 follows.

35 1 represents the top plate whose polished upper surface forms the cooking surface. This plate may be of steel, cast iron or other suitable metal.

40 To the under surface of the plate 1 are attached the two transversely disposed end bars 2 and the center bar 3. The bars 2 are set sufficiently in from the end of the plate 1 and the bars 2 and 3 are short enough 45 to allow the plate 1 to rest on the top of the base B with the bars 2 and 3 within the base, and the bars 2 are spaced inwardly from the ends of the plate 1 for the same purpose.

50 The bars 2 and 3 are secured to the under side of the plate 1 by means of bolts 4. I have shown nine of said bolts employed, one at each end of the bars and one at their centers. The bolt heads are countersunk 55 below the top surface of the plate 1 and the

depression over the bolt head being filled level with the top of the surface with added metal by welding, as indicated at 5, and the weld being then ground and polished to produce a smooth surface uniform with the remainder of the plate. 60

6 represents the front and rear bars of the structure, being angle-bars with their vertical flanges turned downwardly and their horizontal flanges turned inwardly. The 65 bars 6 are stepped inwardly from the edge of the plate 1 so as to be within the base B when the griddle is in place, the griddle being supported by the plate 1 which rests on the top of the base B and extends horizontally 70 outside of the latter.

The bars 6 are held in place against the under side of the bars 2 and 3 by means of the end bolts 4 which extend through the bars 6, nuts 7 being screwed on said bolts 75 up against the bars 6.

Between the bars 2 and 3, the horizontal flanges of the bars 6 are thickened upwardly, as by welding the metal strips 8 thereon, 80 upon which thickened portions rest the ends of the heating elements or heaters D or the blanks D' which may be substituted for certain of the heating elements when the degree of heat to be employed is less than that furnished by a full set of heating elements. The 85 end portions of said heaters are reduced in thickness from below, and there is a slight clearance or looseness of fit so that expansion is allowed for. The shoulders 9 on the underside of the heaters clear the bars 6 sufficiently to permit longitudinal expansion 90 without binding and they also prevent contact between the electric terminals 10 of the heating elements and adjacent portions of the griddle structure should the heaters be 95 misplaced relative thereto.

100 11 is a pressure plate which is attached to the bars 2 and 3 and bears upwardly on the heaters, thus insuring good terminal contact between the heaters and the top plate.

The plate 11 is sufficiently narrow to avoid contact with the terminals 10.

The three bolts 4 which extend through the centers of the bars 2 and 3 also extend through the plate 11 and the nuts 7 are 105 screwed up against said plate.

110 12 represents bolts which secure the corners of the plate 11 to the bars 2, said bolts having their heads countersunk into the upper surfaces of the bars 2 to enable the

top plate 1 to fit flat on the bars, and nuts 13 being screwed up on said bolts 12 against the plate 11.

5 The plate 11 provides a thermal path to disseminate heat from the lower sides of the heaters D and the bars 2 and 3, and from the blanks or spacers D' which may be substituted for some of the heaters D.

10 When in use the top griddle is mounted on the top of the walls of the base in the manner shown in Figs. 1 and 5, the top plate 1 supporting the top griddle in place.

15 When inspection or repairs are necessary, the top griddle may be turned up on its rear edge, whereupon its parts are fully exposed, and after the pressure plate 11 and one of the angle-bars 6 have been removed, one or more of the heating elements may be lifted out and new ones inserted very quickly by 20 an unskilled person, without requiring any tools but a wrench and screw driver for removing the nuts and terminal screws.

25 The base B is an open topped box formed of sheet metal, and preferably provided with an interlining of heat insulating material, and having its bottom edges rolled inwardly and upwardly, as at 14, around a stiffening wire or rod 15.

30 The insulator pan F is formed of sheet metal closed at the bottom and open at its top. It is supported in position in the base B by means of vertical supports or legs 16 which are angular in cross section and fit on the corner of the pan and are spot welded or otherwise attached thereto. The lower 35 ends of the supports 16 rest on the bottom roll 14.

17 and 18 are two spaced apart sheet metal channel members set on edge and turned 40 toward each other with their lower flanges spot welded to the floor of the pan F longitudinally thereof and spaced inwardly from the front and rear walls of the pan. The insulating member E, which is preferably a 45 mat of asbestos felt or similar material is fitted and contained between said channel members 17 and 18.

To enable the mat to be conveniently placed in position, the top flange of one of 50 said members, as at 18, is cut away at spaced intervals to leave tongues 19 which may be bent up to permit the mat to be inserted in place and then bent back into a horizontal position to hold it in place.

55 The conductors 20 which supply the current to the heating elements C are led up through insulated holes 21 in the floor of the pan F at the rear of the channel member 18 and attached to the proper terminals 10.

60 The other ends of the conductors are connected to the switches 22 in the lower portion of the base whose pointer knobs 23 are on the front of the base. Sufficient slack is provided in the conductors 20 to permit the 65 griddle top A to be tilted up on its rear

edge. 24 represents the leads which supply current to the switches.

The feet C are preferably of cast metal and have their upper portions formed to fit in the angles of the base B around the roll 14 and in the angles of the lower portions of the supports 16. 25 represent bolts which extend through the legs C, the supports 16 and the wall of the base B to clamp the supports and legs in place.

70 The bottom of the base B is removable and is comprised of two metal sheets 26 of proper size to fit within the base and be supported by the roll 14. The adjacent edges of said sheets are upset downwardly to form the hooked flanges 27 and 28 is a sheet metal locking member which is forced into said flanges, thus pressing the sheets apart and locking them in place to form the bottom. The ends of the flanges are 80 cut off at one side of the sheets and the member 28 is of slightly less length than the width of the bottom sheets so that it may be inserted after the sheets 26 are in position, thus wedging the sheets into place and locking their adjacent edges together. One end of the member 28 is flanged downwardly as at 29 to form a handle by which the member 85 may be gripped for its insertion or removal.

What I desire to claim is:

1. In an electric griddle, the combination of a top sheet, a pair of bars attached to the underside of said top sheet and in spaced relation thereto, heating elements supported in place beneath said top sheet by having their ends resting on said bars, and a second sheet mounted beneath said heating elements and supporting the intermediate portions of the same from below.

2. In an electric griddle, the combination of a top sheet, a plurality of parallel bars in spaced relation and secured to the underside of said top sheet, a pair of bars disposed at right angles to said first named bars and attached thereto, and electric heating elements having their ends supported on said second named bars and being covered by said top sheet.

3. In an electric griddle, the combination of a top sheet, a plurality of parallel bars in spaced relation and secured to the underside of said top sheet, a pair of bars disposed at right angles to said first named bars and attached thereto, electric heating elements having their ends supported on said second named bars and being covered by said top sheet, and supporting means attached to the first named bars and engaging the intermediate portions of the heating elements from below.

4. In an electric griddle, the combination of a top sheet, a plurality of parallel bars in spaced relation and secured to the underside of said top sheet, a pair of bars disposed at right angles to said first named

- bars and attached thereto, electric heating elements having their ends supported on said second named bars and being covered by said top sheet, and a pressure sheet attached to said first named bars and supporting said heating elements from below.
5. In an electric griddle, the combination of a top sheet, a plurality of parallel bars in spaced relation secured to the under side 10 of said sheet, a pair of bars disposed in angular relation to said first named bars and attached at the ends of the latter, heating elements positioned beneath the top sheet by having their ends supported by said 15 second named bars, and a second sheet supporting the intermediate portions of said heating elements from below.
6. In an electric griddle, the combination of a top sheet, a plurality of parallel bars 20 in spaced relation secured to the under side of said sheet, a pair of bars disposed in angular relation to said first named bars and attached at the ends of the latter, heating elements positioned beneath the top sheet 25 by having their ends supported by said second named bars, and a second sheet supporting the intermediate portions of said heating elements from below and attached to said first named bars.
- 30 7. In an electric griddle, the combination of a top sheet, a plurality of bars spaced apart in parallel relation and attached to the under surface of the top sheet, a pair of angle irons having their vertical flanges turned downwardly and their horizontal 35 flanges turned inwardly attached at the ends of said first named bars, and electric heating elements positioned beneath the top plate by having their ends supported by said angle-bars, the horizontal flanges of said 40 angle-bars being thickened upwardly between said first mentioned bars to position said heating elements in juxtaposition to said top plate.
8. A base for an electric griddle comprising a box formed of sheet metal having its lower edges rolled inwardly to strengthen the box, and a bottom for said box comprised of a pair of metal sheets resting on said roll and means for forcing said sheets 45 apart to wedge them in place.
9. A base for an electric griddle comprising a box formed of sheet metal having its lower edges rolled inwardly to strengthen the box, and a bottom for said box comprised of a pair of metal sheets resting on said roll, the adjacent edges of said sheets being provided with opposed hooked flanges, and a locking member adapted to be forced inwardly into engagement with 55 said flanges to wedge said sheets in position.

Signed at Pittsburgh, Pa., this 3rd day of Sept., 1925.

KARL EHRGOTT.
